UNITED STATES PATENT OFFICE.

WILLIAM T. STRIDE, OF ROCHESTER, NEW YORK.

CARPET-WASHING MACHINE.

Application filed February 16, 1923. Serial No. 619,496.

This invention relates to machines for washing and cleansing carpets, rugs and the like, of a type equipped for automatic operation to support and move the rug to operative stations equipped with improved vacuum, scrubbing and rinsing mechanism and devices. A principal object of the invention is to provide a machine of this character that is relatively simple in construction, and embodies mechanism for first beating and vacuum cleaning the rug, then subjecting the rug to improved scrubbing devices having means associated therewith for supplying automatically a suitable cleansing solution of soap or the like, and finally rinsing the rug with the employment of vacuum means in proximity to the rinsing station for drying the rug. A further object is to provide an improved arrangement of parts and system of connections whereby all of the operative instrumentalities are rendered inoperative upon the lifting of the vacuum nozzle. A still further object has to do with an improved mounting and means of operating the scrubbing brushes of the machines.

Referring to the drawings:

Fig. 1 is an end view of a machine embodying the invention;

Fig. 2 is a front view of one end portion of the machine;

Fig. 3 is a relatively enlarged front view with parts in section showing an intermediate portion of the main operative elements;

Fig. 4 is a sectional view on line 4-4 of Figure 3;

Fig. 5 is a detail cross section on line 5-5 of Figure 3;

Fig. 6 is a detail elevation with an intermediate portion broken away of the first soap discharge tube;

Fig. 7 is a similar elevation of the second soap discharge tube;

Fig. 8 is a transverse section on line 8-8 of Figure 6;

Fig. 9 is a transverse section on line 9-9 of Figure 7;

Fig. 10 is a detail plan view showing a portion of the beater mechanism;

Fig. 11 is an end view thereof; and

Fig. 12 is a fragmentary section showing part of the feeding belt on line 12-12 of Figure 2.

A suitable housing framework 1 composed of two spaced apart side portions is equipped in the lower portion thereof with spaced apart bearings 2, 3 adapted to receive shafts 4, 5 respectively, the shaft 4 being driven by suitable operative connections (not shown). These shafts are spaced apart a distance so that the moving platform to be described, which is mounted thereon, presents an upper stretch sufficient for the proper mounting of the rug cleansing instrumentalities thereover. The rug or other fabric to be cleansed is applied to and borne by a suitable endless carrier mounted on these shafts 4, 5; such endless carrier may within the contemplation of the invention be of any suitable type, such as a canvas belt, but preferably and as herein shown, it comprises a traveling platform mounted upon pairs of sprocket wheels 6, 7 fixed on the respective shafts 4, 5, these sprocket wheels bearing chains 8, which may be of the so-called "link-belt" type, the pairs of these sprocket wheels being spaced apart on the shafts 4, 5 a distance corresponding to the maximum width of carpet or rug for which the machine is designed. These chains have fixed thereto the ends of plates or strips 9 which may be either of metal or wood. These strips 9 are provided with suitable means to hold the carpet securely thereon and prevent slipping thereof. Such means may be of any desired type, but I preferably provide the surfaces of these strips with burrs or small projections. This may be conveniently accomplished by securing relatively thin metallic plates or sheets 10 to the outer sides of the strips 9, these plates 10 having a multiplicity of small holes struck upward therethrough providing burrs 10^a, which project a small distance from the plates but not sufficiently to interfere with the beating and cleansing devices to be described. The framework 1 has each side portion thereof provided with an upright column 1^a which serve as mountings for a beam 11, the ends of which are fitted for vertical adjustment in bearing ways 12 of the column portions 1^a. This beam 11 serves as a mounting and support for the operative instrumentalities to be described, and for this purpose is suitably recessed as will appear later. For adjusting this beam so as to bring the beating and scrubbing

elements into proper co-operative relation with carpets of any thickness, threaded stems 13 are engaged with the ends of the beam, these stems being fitted and held 5 from endwise movement in bearings 14 of the framework and they are equipped with suitable provision for manual adjustment, shown as bevel gears 15 operated by a short shaft 16 journalled in the framework and 10 having a hand wheel 17 at the outer end thereof. For clamping the beam 11 in adjusted position, clamp bolts 18 are provided which extend through, and have heads engaging flanges 11^a at the ends of the beam, 15 these clamp bolts passing through vertically elongated slots 19 in the columns 1^a and having clamping nuts 20 with handles 20^a engaged with the outer ends thereof. The intermediate portion of the rug carrier composed of the plates 9 is supported by a suitable platform 21 borne by the framework to prevent sagging thereof under the action 20 of the cleaning devices. The carrier advances the rug in the direction of the arrow 25 A, i. e. from left to right as seen in Figures 1 and 4, and the rug is first engaged by a beater which comprises a grid 22. This grid is composed of a skeleton frame 22^a extending the width of the machine with its 30 ends having arms 22^b extending therefrom, and with taut wires or thin strips 22^c extending thereacross at intervals longitudinally and transversely. The arms 22^b are fixed in sockets of lugs 23^a which are borne 35 by ring members 23 that are journalled to turn on hubs 24 borne by brackets 25 secured to the framework. The arms 22^b extend beyond the lugs 23^a with their extremities engaged as indicated at 26 by one end 40 of coil springs 27, the other ends of which are anchored to the brackets 25 and which thus tend to draw the beater down upon the carpet. The ring members 23 are provided with lugs 28 adapted to be engaged by short 45 arms 29 fixed to a shaft 30, which is journalled eccentrically in the hubs 24. The shaft 30 is driven at a fairly rapid rate by suitable operative connections (not shown) in a clockwise direction as seen in Figures 50 4 and 11, and the lugs 28 are so located on the ring members 23 that the arms 29 will engage them to lift the beater against the tension of the springs 27 at each rotation of the shaft 30, the length of the arms 29 55 being such that when the beater has been lifted to a suitable extent, the ends of the arms 29 will be disengaged from the lugs 28 owing to the eccentricity of the shaft 30, and thus the beater be permitted to snap 60 back under the action of the springs 27 to strike the carpet with a substantial impact. The carpet is next acted on by vacuum nozzles which serve to remove all foreign matter in the fabric which has been released by 65 the beater while the carpet is still dry. For

this purpose suction nozzles 31 are mounted for vertical adjustment on the front side of the beam 11, these nozzles being adapted to be operated to let them down into operative engagement with the carpet, or drawn 70 upward to inoperative position at will by suitable connections shown as cords 32, engaged with lugs 31^a of the nozzles, these cords being illustratively shown as extending around overhead pulleys 32^a and downward to a position convenient to the operator. It is here to be understood that these suction nozzles and the other operative devices to be described including the scrubbing mechanism and the rinsing and drying 80 means are constructed and arranged in a series of units extending across the width of the machine, these units having common power operating, and fluid supply connections. These operative units are preferably 85 each of a width of about twelve inches and they are so arranged that any number of them beginning at one side of the machine may be disabled and rendered inoperative so that the machine is thus rendered adaptable 90 for carpets or rugs of varying widths. Since these operative units are all alike a description of one thereof will serve for all. Each vacuum nozzle 31 comprises a nozzle extremity 31^b of a width corresponding to that 95 of the cleaning unit with which it is associated, this leading into an upper relatively larger tubular portion 31^c which is slidably fitted in a sleeve 33, which is connected with and depends from a suction head 34 100 extending across the machine and connected with a suitable source of vacuum generation (not shown), there being thus one of these sleeves 33 depending from the suction head 34 at the locality of each of the cleansing 105 units. Each of the tubular nozzle portions 31^c has journalled diametrically therein a shaft 35 which has fixed thereon a wing valve gate or damper 36, which when turned transversely of the nozzle is adapted to close 110 the same, while when it is turned in parallelism with the nozzle as shown the nozzle is open. This valve gate is controlled by a pinion 37 fixed on an end of the shaft 35, which extends outward through an elongated slot 38 of the sleeve 33. The pinion 37 meshes with a rack 39, which is fixed to the beam 11. Thus when the nozzle 31 is lowered to operative position, the valve gate 36 is automatically turned to open position, 120 while when the nozzle is lifted, the valve is turned to close the nozzle passage and thus disconnect the nozzle from the suction system through the head 34.

40 indicates a pipe extending horizontally 125 relatively close to the path of the moving carpet and directly in advance of the suction nozzle 31. This pipe is adapted to supply cleansing fluid, such as soap solution to the carpet, and for this purpose it has a supply 130

pipe connection 41 leading from a suitable source of supply 42 of such cleansing fluid, which may be located overhead so as to supply the fluid by gravity. The pipe 40 is equipped with a series of holes 40^a extending downwardly therefrom toward the side thereof away from the suction nozzle, and a valve sleeve 43 is fitted to turn on the pipe 40 with holes 43^a therein which in one position of the sleeve register with the holes 40^a to permit discharge of the soap. The sleeve 43 bears an arm 44 extending diagonally upward therefrom when the sleeve is in position so that the holes 40^a, 43^a are in register with the holes 40^a to stop the soap discharge. The length of the arm 44 is such that the projection 31^a remains in contact therewith at the upper limit of movement of the nozzle, so as to keep the soap discharge closed. Coil springs 45 are provided having a fixed anchorage at one end and engaged at their other ends with the tube 43, these springs tending constantly to turn the sleeve to valve opening position so that the discharge of soap may begin as soon the suction nozzle is lowered and the machine started in operation. It will be understood that separate soap discharge devices as described are provided for each of the cleaning units, all of these however, having common connection with the overhead soap supply conduit 42 which may lead from a reservoir or supply tank 42^a containing a substantial quantity of the soap or cleansing fluid. The described provision for closing soap ports 40^a may be utilized to shut off any soap drip at once after the unit has been rendered inoperative. I preferably provide individual manually controlled shut-off valves 41^a in the pipe connections 41 which may be closed before the vacuum nozzle is raised or before the end of the rug reaches the first row of brushes. One or more scrubbing devices are provided for each cleaning unit, there being two such devices shown for illustrative purposes arranged one in advance of the other in the direction of rug movement, though it is to be understood that it is within the contemplation of the invention to use if desired, only one such device or any plurality thereof as may be needed or preferred for the particular character of work. The beam 11 is hollowed out interiorly providing two spaced apart compartments 11^b, 11^c opening downward which have the respective scrubbing devices and their operating connections fitted therein. These scrubbing devices are respectively operated by shafts 46, 47 journalled in bearings of upward projections 11^d from the beam 11 and driven by suitable power connections (not shown). Since these scrubbing devices are alike, the description of one of them will suffice for both. A stiff brush 48 of substantial thickness and of a length corresponding to the width of the unit is mounted in a head 49, which is slidably fitted in a socket 50. A spring 51 mounted in the socket 50 engages the head 49 to press the brush yieldingly downward upon the carpet, while spring detents 52 borne by the socket engage the lower edge 75 of the head 49 to limit the downward movement thereof, while permitting the head to be removed by pressing these detents outward when desired. Each socket 50 is fitted to slide horizontally in the beam 11 lengthwise thereof, i. e. in a direction transverse of the direction of carpet movement. This socket has pivoted thereto intermediate its length at 55^a one end of a link 53, the other end of which is pivoted at 54 to one end of a link 55, the other end of which is pivoted at 56 to the beam. It will be noted that the links 53, 55 together constitute a toggle which upon the application of a direct downward pressure upon the pivot 54 will act to 80 press the brush socket 50 endwise and thus impart operative movement to the brush. The several brush sockets 50 bearing their respective brushes extend across the width of the rug or carpet and are reciprocated in unison by the described arrangement of links from the cams 61. For this purpose the pivot 54 is connected through a short link 57 with a bar or rod 58 which is fitted to slide vertically in bearings 59 of the beam 100 and bears at its upper end a roll 60 engaging an eccentric 61 fixed on the shaft 46, a like eccentric being fixed on the other shaft 47 for the other scrubbing device. For the return movement of the brush a compression coil spring 62 having backing against the top of the beam reacts against a shoulder at the top of the rod 58 to normally press said rod upward and keep the roll 60 in constant engagement with the eccentric 61. The rug or carpet is thus scrubbed and cleansed by the action of the brushes 48 which are reciprocated with a downward pressing movement thereupon in one direction by virtue of the springs 51 as described and in the presence of the soap solution or like cleansing fluid which has been delivered upon the rug just before it reaches the brushes from the pipes 40. Means is provided whereby the lifting of 120 the suction nozzles to inoperative position will disconnect the power operating connections to the brushes. For this purpose the shafts 46, 47 are made in sections corresponding to the several cleansing units with clutch connections between such sections, the prime driving impulse being imparted from the right hand end of these shafts as seen in Figures 2 and 3, i. e. from the driving pulley 63. As shown, this driving pulley 125 130

is mounted on the shaft 46 and the shafts 46, 47 are geared together adjacent this driving pulley by meshing gears 63^a. It will be noted that in the operation of disconnecting or rendering inoperative certain of the units, those from the left hand end in said figures, i. e. at the opposite side of the machine from the driving connections 63, 63^a, will be first rendered inoperative. For this purpose 10 each suction nozzle 31 is equipped with a projection 64, which is adapted to engage one or the other of collars 65, 66 on a rod 67, which is mounted for vertical movement and bears at its upper end a head 67^a. The 15 head 67^a has a horizontal slot 68 therein which is engaged by a pin 69, which forms the pivot of a toggle composed of short links 70, 71. The link 70 is pivoted at its other end to a pin 72 slidably fitted in the framework and having its outer end engageable with a lateral cam face 73 on a disc 74 fixed on the shaft section 46 which actuates the scrubbing unit. The other link member 71 has its outer end pivoted to a rod 75 20 slidably fitted in the framework and pivoted at its other end intermediate the length of an arm 77. One end of the arm 77 has a fixed pivot on the framework at 78, while its other end engages a groove 79^a in a clutch collar 25 79 slidably keyed on the end of the section of the shaft 46 adjacent to the scrubbing unit under consideration, on the side from which the power is derived. The clutch collar 79 is adapted to engage a co-operative clutch member 80 fixed on the 30 section of shaft 46 pertaining to the unit under consideration. A spring pressed pin 81 engaging a lateral V projection on the rod 75 co-operates to insure the completion 35 of an operative movement of the rod 75 in either direction. With this construction upon the moving upward of the bar 67 by the engagement of the projection 64 with the upper collar 65, the toggle 70, 71 which was 40 before broken, is straightened or extended and the pin 72 is thus moved to the left as seen in Figure 3 to a position where the cam face 73 will engage it as soon as it comes 45 opposite thereto and serve to press the rod 75 endwise to disconnect the clutch collar 79 from the collar 80, the spring pressed pin 81 serving to hold the parts in such disconnected position until the bar 67 is again 50 pulled downward by the lowering of the suction nozzle which serves to break the toggle and to reconnect the clutch as will be 55 readily understood. The location of the cam face 73 is such that it will operate to throw out the clutch connection and thus 60 stop the brush when the toggle 53, 55 is in the position shown at the left in Figure 3, i. e., when the brush and its socket 50 is moved farthest away from the adjacent brush at the right, the purpose of this 65 being so that a disconnected brush head will

not be in the way of the adjacent brush head that is in operation. As already stated the line of brushes 48', which are operated from the shaft 47 and their operating connections are the same as already described 70 for the brushes 48, except that preferably, and as shown, the eccentrics 61 which operate them are disposed opposite the eccentrics on the shaft 46, so that the scrubbing movements of the brushes 48' alternate with those 75 of the brushes 48. Between the line of brushes 48 and the brushes 48' I mount a second pipe system 82 for supplying soap solution or cleansing fluid. The pipe sections of this system are supplied by connections 83 80 from the overhead source 42 with individual hand valves 84. These pipes have downward discharge holes therethrough which are controlled to prevent soap drip by valve sleeves 85 fitted to turn thereon similarly as 85 the sleeves 43, these sleeves 85 having holes adapted to register with the holes in the pipes 82 in one position on the sleeves. The sleeves 85 are equipped with short fingers 86 extending downward and forwardly therefrom and adapted to engage the carpet as it passes thereunder to hold the sleeve with the holes thereof in register with the holes of the pipe 82 so long as the carpet is moving thereunder. Springs 87 are provided with a fixed 90 anchorage at one end and engaging the sleeves 85 at their other ends tending to turn said sleeves so as to close the discharge holes as soon as the end of the carpet passes from under the fingers 86, so that these are permitted to move downward as indicated in Figure 9.

88 indicates a system of pipes extending across the machine directly over the path of the carpet and in advance of the front line of scrubbing brushes 48', adapted to discharge water or steam or a mixture of both, upon the carpet to rinse the same. One of these pipes 88 is provided for each cleansing section or unit and they are preferably fixed to vacuum nozzles 131 adjacent the lower ends thereof by means of suitable brackets 88^a. These pipes are provided with discharge ports 88^b opening downward and they are supplied with steam or hot water from pipe connections 89 which, 110 as shown, include a flexible section 89^a whereby the lower portions thereof with the pipes 88 may be raised with the vacuum nozzles 131. These steam pipe connections may lead through the soap tank 42^a, 115 as seen in Figure 2, so as to keep the soap contents thereof well warmed and thoroughly fluid. Means is provided for taking up and removing from the carpet or rug the rinsing water together with the dirt and 120 cleansing fluid. For this purpose a system of vacuum nozzles 131 is provided at the forward end of the machine to engage the rug after it has passed the scrubbing and 125 rinsing stations. This system of vacuum 130

nozzles may correspond in all particulars with the system of nozzles 31, there being one thereof for each cleansing section or unit with slidable connections into a sleeve 133 depending downward from a suction head 134. It may also be equipped with means 132 for lifting the same and with the valve gate 136 having connections 135, 137, 138, 139 for operating the same, all as already described. In the present illustrative embodiment these vacuum nozzles 131 which may be termed the drying system of the machine are each equipped with connections to render inoperative the respective brushes 48 of the several cleansing units with which they are associated as the several vacuum nozzles are lifted to inoperative position. These connections, as shown, are in all respects similar to those already described for rendering inoperative the brushes 48 as the nozzles 31 are lifted, and hence need not be further explained in detail. It is however, within the contemplation of the invention to provide suitable connections whereby both sets of brushes 48, 48' will be rendered inoperative upon the lifting of the final vacuum or drier nozzles 131. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:—

1. A machine of the kind described comprising a carrier adapted to support a rug and move the same forward, mechanism for preliminarily beating and dry-cleaning the rug equipped with a vacuum head, and mechanism for then scrubbing the rug with a reciprocating movement equipped with provision for supplying cleansing fluid thereto.

2. A machine of the kind described comprising a carrier for supporting and advancing a rug or the like, mechanism for scrubbing the rug with a reciprocating movement equipped with means for supplying cleansing fluid thereto, a rinsing station equipped with provision for forcing water into the rug after it is scrubbed, and drying means comprising a vacuum head mounted for lowering to operative position or raising to inoperative position at will.

3. A machine for cleaning rugs and the like comprising an endless carrier adapted to support and advance the rug, scrubbing devices equipped with means for supplying cleansing fluid to the rug, a vacuum head mounted in proximity to said scrubbing

devices for movement downward to operative position or upward to inoperative position at will, and connections from said vacuum head for rendering said scrubbing devices inoperative upon the lifting thereof. 70

4. A machine for cleansing rugs and the like comprising a movable platform adapted to support the rug and move the same forward, a series of cleansing units arranged side by side extending across the machine, means for operating said units equipped with provision whereby said units may be progressively rendered inoperative beginning with one side of the machine. 75

5. A machine for cleansing rugs and the like, comprising a platform mounted for movement to support and advance the rug to be cleansed, a series of cleansing units extending across the machine, each equipped with a suction head and with scrubbing devices, means for operating said scrubbing devices, and means whereby any desired number of said units may be rendered inoperative at will beginning with one side of the machine. 80 85 90

6. A machine for cleansing rugs and the like, comprising a movable conveyor for supporting and advancing the rug, a plurality of cleansing units extending across the machine, each equipped with a suction head for preliminarily dry-cleaning the rug, means for supplying cleansing fluid, scrubbing devices, means for supplying rinsing fluid and a drier suction head, operating mechanism for said units, and means for progressively disconnecting said units from said operating mechanism beginning with one side of the machine whereby the working dimension of the machine is proportioned to rugs of different sizes. 95 100 105

7. A rug cleansing machine comprising a suction head mounted for movement to operative or inoperative position at will, a scrubbing device equipped with operating connections, and means for disengaging said connections when said suction head is moved to inoperative position and for re-engaging said connections when the suction head is moved to operative position. 110

8. A rug cleansing machine comprising means for supporting and advancing a rug, a suction head mounted for movement to operative or inoperative position with respect thereto, a scrubbing device and means for supplying cleansing fluid equipped with provision for control by the movement of said suction head. 115 120

9. A rug cleansing machine comprising a movable support for a rug, a suction head mounted for movement to operative or inoperative position at will, a plurality of scrubbing devices spaced apart in the direction of rug movement and a plurality of supply conduits for cleansing fluid, one thereof equipped with means for control by the 125 130

movement of said suction head, and the other thereof equipped with means for control by the rug.

10. A rug cleaning machine comprising a movable platform for supporting and advancing the rug, a suction head mounted for movement to operative or inoperative position with respect thereto, a scrubbing device equipped with operating connections, 10 a valve gate controlling said suction head, means for closing said valve gate as the suction head is moved to inoperative position, and means for rendering the operating connections to the scrubbing devices inoperative

by the moving of the suction head to inoperative position.

11. A rug cleansing machine comprising a movable platform for supporting and advancing the rug, means for supplying cleansing fluid thereto, scrubbing devices each consisting in a brush head equipped with means for yieldingly pressing it upon the rug, and operating connections including a toggle device for reciprocating said brush heads transversely of the direction of rug movement. 20 25

In testimony whereof, I have signed my name to this specification.

WILLIAM T. STRIDE.
